UNITED STATES PATENT OFFICE.

OLE MICKELSON, OF HOQUIAM, WASHINGTON.

SAFETY LOCK FOR LOGGING HOOKS.

Application filed November 1, 1922. Serial No. 598,406.

To all whom it may concern:

Be it known that I, OLE MICKELSON, a citizen of the United States, residing at Hoquiam, in the county of Grays Harbor and State of Washington, have invented a new and useful Safety Lock for Logging Hooks, of which the following is a specification.

This invention relates to logging hooks and more particularly to locking devices therefor.

The object of the invention is to provide a strong, cheap and efficient hook of this character having means to close the bill and prevent the article engaged by the hook from being accidentally separated therefrom.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a side elevation of a logging hook equipped with one form of this invention.

Fig. 2 is a top plan view thereof with the lock shown in operative position.

Fig. 3 is a side elevation showing another form of the invention applied.

Fig. 4 is a plan view of the form shown in Fig. 3 with the lock in operative position.

Fig. 5 is a side elevation showing still another form of the invention.

Fig. 6 is a plan view thereof.

Fig. 7 is the side elevation of still another form of the invention.

Fig. 8 is a top plan view thereof, and

Fig. 9 is a transverse section through the locking pin.

In the embodiment illustrated in Figs. 1 and 2, a clevis C having the usual apertured arms to receive a connecting pintle which is here shown at 5.

The logging or butt hook 1 has the usual shank 2 provided at its free or outer end with an eye 3 for the passage therethrough of the pintle 5 which connects the hook with the clevis. The bill 4 of the hook is shown spaced from the connection of the hook with the clevis a sufficient distance to permit a logging chain or a tag line to be inserted.

The pintle 5 is here shown provided at the end adjacent the bill 4 of the hook with an enlarged disk-like head 6 having a recess 7 in its perimeter which is designed to be turned into register with the bill 4 of the hook when it is desired to release the hook from the tag line. The turning of the disk 6 into the position shown in Fig. 2, will close hook 1 and prevent all possibility of the tag line or logging chain which is connected therewith from being accidentally disengaged, the pull which is exerted on clevis C being in a direction opposite to that exerted on the hook 1 so that the pintle 5 is held against turning thus preventing all possibility of the recessed disk 6 turning to bring the recess 7 into register with bill 4 and thereby release the tag line. When the strain is relieved on the clevis and hook, obviously the pintle 5 may be freely turned to bring the recess in the disk 6 opposite the bill 4 of the hook to permit the tag line to be taken out.

While this hook is designed primarily for use on the tag line of a logging apparatus, obviously it may be used for any other purpose.

In logging operations employing speed, donkey engines, there are two lines used, one being the main line which hauls the log in to the landing, and the other the haulback which takes the main line back into the woods. Between the main and the haul back line is a tag line with which the clevis C of this hook is engaged. The bill 1 of the hook is designed to be engaged with what is known as a choker which is a cable or chain that encircles the log to be manipulated. In steep and rough country, it is oftentimes very difficult to prevent the choker from slipping off the butt hook and it is to overcome this difficulty that this invention is designed.

In the form shown in Figs. 3 and 4, the clevis C is substantially the same as that shown in the other figures and is designed to be used for the same purpose. The hook 1 used in this form is substantially the same as that shown in the other figures, the difference in this structure being that the locking disk, instead of constituting the head of the connecting pintle 5^a, is made separate and loosely mounted on the pintle between the clevis and the eye 3^a of the hook.

The locking disk 9 which is mounted on the pintle 5^a has a recess 7^a in its perimeter

which is designed when turned into register with the bill 4^a of the hook to release the tag line, and when said disk is rotated to place this recess out of register, the pull exerted on 5 the clevis and the hook will prevent rotation of the disk and securely close the hook against disengagement.

In the form shown in Figs. 5 and 6, the structure is substantially the same as that 10 shown in Figs. 3 and 4 except that the hook 1^b is arranged in a plane at right angles to that shown in the other figures so that the disk 10 is in the same plane as the hook and 15 is equipped with a recess 11 in its periphery to register with the bill of the hook when it is desired to release the tag line.

In the form shown in Figs. 7 and 8, the hook 1^c has the bill 4^c thereof twisted or deflected laterally as shown clearly in Fig. 7 20 to position it adjacent the disk-like head 12 of the pintle 13 which connects the eye of the hook with the clevis C. This disk-like head 12 is recessed as shown at 14, which recess is designed to be positioned opposite the 25 bill 4^c of the hook when the tag line or other object engaged by the hook is to be released. An auxiliary lock for the disk 12 is shown in the form of a pin 15 which is loosely mounted in the disk 12 and is designed to drop 30 down into position to engage the shank of the hook 1^c to prevent turning of the disk so that the recess 14 therein will not register with the bill of the hook until this pin is lifted. This pin 15 is provided with a longitudinally extending key 16 which lies in a 35 lateral extension 17 opening through one side wall of the aperture of the disk in which the pin is mounted so as to prevent turning of the pin. This pin 15 has a head 18 at one 40 end and its other end may be equipped with any suitable means for preventing the withdrawal of the pin, it being preferably upset for this purpose.

From the above description it will be obvious 45 that the various forms of locks shown will all reliably close the entrance to the

hook and prevent disengagement therefrom of the article held thereby.

I claim:—

1. A butt hook for logging apparatus having a shank with an eye at one end and a bill at the other, a pintle to extend through the eye in said shank, and a disk-like locking member fixed to said pintle and having a recess in its periphery to register with said bill for releasing the article engaged by the hook, the pull on the hook operating to hold the pintle against turning. 50

2. A hook of the class described comprising a shank with an eye at one end, a pintle rotatably mounted in said eye and having a disk-like head fixed at one end to be positioned adjacent the bill of the hook, said head having a recess in its periphery adapted when the pintle is turned a predetermined distance to register with the bill of the hook to provide for the application and release of the article to be engaged by the hook. 60

3. A hook of the class described comprising a shank with an eye at one end, a pintle to be mounted in said eye and having a disk-like head fixed one end to be positioned adjacent the bill of the hook, said head having the recess in its periphery adapted when the pintle is turned a predetermined distance to register with the bill of the hook to provide for the application and release of the article to be engaged by the hook, said disk-like head having a pin 70 loosely mounted therein to drop into engagement with the shank of the hook to prevent turning of the pintle beyond a predetermined point. 75

In testimony that I claim the foregoing as 80 my own, I have hereto affixed my signature in the presence of two witnesses.

OLE MICKELSON.
